By # UNITED STATES PATENT OFFICE.

GEORGE F. A. BRUEGGEMAN, OF ST. LOUIS, MISSOURI.

DOOR.

1,312,155.

Specification of Letters Patent. Patented Aug. 5, 1919.

Application filed April 22, 1918. Serial No. 230,093.

To all whom it may concern:

Be it known that I, GEORGE F. A. BRUEGGEMAN, a citizen of the United States, residing at city of St. Louis, State of Missouri, 5 have invented a certain new and useful Improvement in Doors, of which the following is a full, clear, and exact description, such as will enable others skilled in the art to which it appertains to make and use the 10 same, reference being had to the accompanying drawings, forming part of this specification, in which,—

Figure 1 is a side elevational view of my improved door.

Fig. 2 is a horizontal sectional view of the same.

Fig. 3 is a detail view on line 3—3 of Fig. 1.

Fig. 4 is a detail view.

This invention relates to a new and useful improvement in doors or inclosures having openings such as windows and the like, elevators, etc., where it is desired that the door or shutters may be arranged either 25 singly or in pairs, may be set on the face of the wall, or in pockets, giving the greatest available space when opened and without interfering with surrounding objects.

The door as an entirety is made up of 30 panels which may be of wood, glass or fire-proof material, designed to slide over each other to form a solid wall when the door is closed, said panels being operated by suitably arranged counter-balanced arms, so 35 interconnected that the door, or the panels thereof, can readily be locked either in open or closed position.

In the drawings, 1 indicates the casing or wall of the building from which extend 40 posts 2 arranged one above the other and which posts are preferably squared or non-circular in cross section and on which are arranged arms 3 designed to be operated in unison, said arms being spaced apart by 45 washers 4. These posts 2 are pivotally arranged in the door casing and constitute the pivotal support for the arms 3 which are mounted thereon and rotatable therewith. These arms are of different lengths and are 50 pivotally connected at their outer ends to panels or door sections 5, the shortest pair of arms being connected to the door panel nearest the posts 2, while the longest pair of arms are connected to the outermost door 55 panel. These door panels 5 are preferably provided with overlapping flanges 5^a which,

when the door acts as a closure, are in close proximity to each other so as to practically provide a solid wall. Each panel as shown in Fig. 4 is provided with oppositely extending flanges 5^a substantially throughout 70 its entire length, thus forming a panel which is Z-shape in cross section and when the door is open the overlapping flanges 5^a may serve as stops, as the weight of the open door will bring them into close contact with 75 each other. By this construction, space is also provided for the movement of arms 3 connected to the intermediate panels and consequently when the door is closed the 80 panels and arms will be nested close together.

6 indicates a connecting rod pivotally attached to a pair of arms and carrying a locking bar 7 whose extremity may engage a keeper in the wall or lintel to lock the door in its opened or closed position.

8 indicates a connecting rod preferably mounted on the uppermost post 2 and pivotally connected to the point of connection of the lowermost longest arm 3, to the outermost panel. This rod 8 is made up of two parts 90 pivotally connected together and when the door is fully distended serves to prevent the same from sagging and in this manner relieving the flanges 5^a from the strain of supporting the panels in position.

9 is a counter-balancing weight arranged on the cord or cable 10 passing over an idle pulley 11 and connected to the upper end of the outermost panel 5.

The operation of the door is very simple. 100 When the joint in connecting rod 8 is broken and the bolt 7 retracted, the panels of the door may be moved upwardly and folded into a receiving pocket at one side of the casing, as shown by dotted lines in Fig. 1, 105 the counter-balancing weight assisting in lifting the panels. The arms 3 are designed to move in unison and consequently the panels are caused to maintain parallelism in their movement to and from their opened 110 and closed position.

I claim:

1. A door composed of a plurality of sets of supporting arms, the arms of each set being spaced apart, said arms being of different lengths, and panels pivotally connected to the outer ends of said arms, intermediate panels having flanges at their outer edges lying in the plane of movement of said arms, in combination with means for supporting 120 said door.

2. A door composed of a plurality of sets of supporting arms, the arms of each set being spaced apart, said arms being different lengths, panels pivotally connected to the outer ends of said arms, intermediate panels having flanges at their outer edges lying in the plane of movement of said arms, and said intermediate panels also having flanges at their inner edges which overlap said outer flanges and lie in the plane of the supporting arms, in combination with means for supporting the door.
3. A door composed of a plurality of sets of arms pivotally mounted on a door casing, said arms being spaced apart and of different lengths, panels pivotally mounted upon the outer ends of said arms, the intermediate panels being designed to move in the space between the intermediate arms, in combination with a hinged connecting bar designed

to be pivotally mounted on the door casing and pivotally connected to the outermost panel, and means for operating said door.

4. A door composed of a plurality of sets of arms pivotally mounted on a door casing, the arms of each set being spaced apart and of different lengths, panels pivotally supported by the outer ends of said arms, the intermediate panels being designed to move in the spaces between the outside arms, and a lock for locking said panels in their opened and closed positions.

In testimony whereof I hereunto affix my signature in the presence of two witnesses, this 17th day of April, 1918.

GEORGE F. A. BRUEGGEMAN.
